UNITED STATES PATENT OFFICE.

EMERY REED, OF NEW YORK, N. Y.

LIQUID-DISPENSING NOZZLE.

Application filed October 22, 1920. Serial No. 418,789.

To all whom it may concern:

Be it known that I, EMERY REED, a citizen of the United States, and resident of the borough of Manhattan, in the city and State 5 of New York, have invented a new and useful Improvement in Liquid-Dispensing Nozzles, of which the following is a specification.

The object of my invention is to provide 10 a liquid dispensing nozzle with a normally closed discharge valve which will be automatically opened when the delivery pressure of the liquid is greater than the closing pressure on the valve.

15 My invention is particularly directed to an improvement in the dispensing nozzle located at the free end of the flexible hose which leads from a gasoline pump, whereby the gasoline which is left in the 20 flexible hose will be retained therein so that each purchaser of gasoline will receive exactly the amount of gasoline registered by the pump, the valve at the same time serving to prevent leakage at the nozzle, and being so arranged that it cannot be tampered with at the exterior.

A practical embodiment of my invention is represented in the accompanying drawing, in which,

30 Fig. 1 represents the liquid dispensing nozzle in top plan.

Fig. 2 represents the same in side elevation.

Fig. 3 represents a section taken in the 35 plane of the line III—III of Fig. 1.

The flexible hose which leads to the gasoline pump, not shown herein, is denoted by 1. It may be provided with a nipple 2 by means of which it may be secured to the 40 branch 3 of the dispensing nozzle by means of a suitable union 4.

The dispensing nozzle is provided with a partition 5 upon one side of the lateral supply port 16, which partition forms the bottom of a recess 6. A suitable cap 7 serves to close the mouth of the recess 6. The nozzle is provided with a partition 8, upon the other side of the lateral supply port 16, which partition has a discharge port 9 there- 50 through.

At the discharge end of the nozzle, a strainer 10 may be located, which strainer is held in position by a union 11, which engages the nozzle and also the flange of a nozzle extension 12.

The head 13 of the discharge valve serves to open and close the discharge port 9. The valve stem 14 extends through the partition 5, into the recess 6 where a spring 15 engages the stem for normally holding the discharge valve closed. It is intended that this spring shall be sufficiently powerful to hold the valve closed against the weight of the liquid in the line back of the valve except when the delivery pressure is exerted on the 65 liquid as for instance, by the operation of the pump. This delivery pressure will be greater than the pressure of the spring 15, thereby automatically opening the valve. The moment the delivery pressure stops, the 70 valve will automatically close, thus holding the liquid in the line back of the valve so that on the next operation of the pump, the discharge of the liquid from the nozzle immediately begins.

75 By the provision of this automatic discharge valve in the dispensing nozzle, an accurate measured supply of the liquid is ensured for each customer, thereby eliminating all discussion as to who is entitled 80 to the liquid in the line beyond the pump, as so frequently happens in the type of liquid supply to which this invention is directed.

It is evident that various changes may be 85 made in the construction, form and arrangement of the several parts without departing from the spirit and scope of my invention; hence I do not intend to limit myself to the particular embodiment herein shown and described, but,

90 What I claim is:—

1. A liquid dispensing nozzle having a lateral supply port, a partition forming a recess on one side of the supply port, a partition having a discharge port therethrough 95 on the other side of the supply port, a valve for the discharge port having its stem extending into said recess, and a spring in said recess engaging said stem to normally hold the valve closed.

2. A liquid dispensing nozzle having a lateral supply port, a partition forming a recess on one side of the supply port, a partition having a discharge port therethrough
5 on the other side of supply port, a valve for the discharge port having its stem extending into said recess, a spring in said recess

engaging said stem to normally hold the valve closed, and a cap for closing the mouth of said recess.

10

In testimony, that I claim the foregoing as my invention, I have signed my name, this 18th day of October, 1920.

EMERY REED.
